WITNESS:

George E. Bast
INVENTOR
BY Victor J. Evans
ATTORNEY

UNITED STATES PATENT OFFICE.

GEORGE E. BAST, OF EVERETT, WASHINGTON.

CAP-FORMING DEVICE.

Application filed June 10, 1922. Serial No. 567,365.

To all whom it may concern:

Be it known that I, GEORGE E. BAST, a citizen of the United States, residing at Everett, in the county of Snohomish and 5 State of Washington, have invented new and useful Improvements in Cap-Forming Devices, of which the following is a specification.

This invention relates to an improved 10 tool or resizer, primarily adapted for reshaping the flanges of jar closures.

An object of the present invention is the provision of a tool for this purpose, which is simple in construction, efficient in use 15 and which may be operated for straightening or reshaping the flanges of jar closures without danger of damage to the usual porcelain lining.

With the above and other objects in 20 view, the invention further includes the following novel features and details of construction, to be hereinafter more fully described, illustrated in the accompanying drawings and pointed out in the appended 25 claim.

In the drawings:—

Figure 1 is a side elevation of the invention showing a jar closure or cap in place.

Figure 2 is a central sectional view of 30 the same.

Referring in detail to the drawings, wherein like characters of reference denote corresponding parts, the reference character 10 indicates a base or male member which is provided at one end with a 35 reduced tapered circular extremity 11, while at the inner end or base of the said reduced tapered extremity 11 there is provided an annular outwardly extending inclined 40 flange 12.

Co-operating with the male member 10 is a female member 13, the latter being provided with a depression or socket 14 for receiving the reduced tapered extremity 11 of 45 the male member 10 and also for receiving a jar cap or closure 15. The mouth of the socket 14 of the female member is surrounded by an outwardly inclined or beveled edge 16 which co-operates with the annular inclined flange 12.

As illustrated in the drawings, the cap or closure 15 is placed upon the reduced tapered extremity 11 of the male member 10 with the flange of the cap resting upon the flange 12 of said member. The female 55 member 13 is then positioned over the cap or closure 15 and its beveled edge 16 will rest upon the opposite side of the cap flange. Rotary or reciprocatory motion is thus imparted to the female member 13 60 with a slight downward pressure, whereupon the engagement of the flange 12 and the beveled edge 16 will straighten out any irregularities of the flange so that the latter will accurately seat upon the usual rubber gasket of a jar. 65

In order to provide convenient means whereby the female member 13 may be rotated, the latter is provided with a gripping flange 17 around its outer periphery. 70

The top of the female member 13 is provided with an opening 18, through which the finger may be inserted for the purpose of forcing the cap outward, when necessary.

The invention is susceptible of various 75 changes in its form, proportions and minor details of construction and the right is herein reserved to make such changes as properly fall within the scope of the appended claim.

Having described the invention what is 80 claimed is:—

A tool of the class described embodying a male member provided with a reduced 85 tapered circular extremity, an annular inclined outwardly extending flange located at the base of the tapered extremity, a female member having a socket for the reception of the tapered extremity of the male member and capable of rotation on said 90 male member, an annular beveled edge surrounding the mouth of the socket and co-operating with the inclined outwardly extending flange and a gripping flange located upon the outer surface of the female 95 member whereby the female member may be rotated.

In testimony whereof I affix my signature.

GEORGE E. BAST.
